REFRACTOR FOR LIGHTING FIXTURES AND THE LIKE

Vearl S. Wince, Newark, Ohio, assignor to Holophane
Company, Inc., a corporation of Delaware

Filed Dec. 11, 1963, Ser. No. 77,757

Term of patent 14 years

(Cl. D48—16)

T 19.1.

T 19.2.

FIG. 1 is a perspective view of the refractor according to the invention.

FIG. 2 is an end view of the refractor.

FIG. 3 is a top plan view of a portion of the refractor and it is to be understood that the portions shown in full lines continue throughout the broken line disclosure.

FIG. 4 is a bottom plan view of a portion of the refractor and it is to be understood that the portions shown in full lines continue throughout the broken line disclosure.

I claim:

The ornamental design for a refractor for lighting fixtures and the like, substantially as shown and described.
